DOLL

Dora Marcus, 345 8th Ave., New York, N.Y. 10001

Filed July 28, 1971, Ser. No. 167,074

Term of patent 14 years

Int. Cl. D21—01

U.S. Cl. D34—4 R

FIG. 1 is a rear elevational view of a doll showing my new design;

FIG. 2 is a side elevational view thereof, with certain of the component parts in altered relative condition;

FIG. 3 is a rear elevational view as seen from the lefthand portion of FIG. 2; and

FIG. 4 is a front elevational view thereof.

I claim:

The ornamental design for a doll, substantially as shown.
